UNITED STATES PATENT OFFICE.

GRANT HOLMES, OF DANVILLE, ILLINOIS, ASSIGNOR TO ROBERT HOLMES & BROTHERS, OF DANVILLE, ILLINOIS, A CORPORATION OF ILLINOIS.

MECHANISM FOR HANDLING CARS.

No. 891,933.

Specification of Letters Patent.

Patented June 30, 1908.

Application filed March 16, 1908. Serial No. 421,375.

To all whom it may concern:

Be it known that I, GRANT HOLMES, a citizen of the United States, residing at Danville, in the county of Vermilion and State 5 of Illinois, have invented certain new and useful Improvements in Mechanism for Handling Cars, of which the following is a specification, reference being had therein to the accompanying drawings.

10 This invention relates to mechanism for handling cars, and is designed more particularly for handling mine cars in coal mines and similar places.

15 The object of the invention is to provide mechanism by means of which the mine cars will be handled to and from the hoisting cage without the intervention of the operator, and, to this end, it is a further object of the invention to provide such a mechanism comprising a car lift which will be actuated by the downward movement of the cage; to provide a cushioned landing platform for the cage; and to provide an automatically operated cage and sump guard.

20 With these objects in view my invention consists in certain novel features of construction and in certain parts and combinations hereinafter to be described, and then more particularly pointed out in the claims.

25 In the accompanying drawings, Figure 1 is a side elevation of a car handling mechanism embodying my invention; Fig. 2 is a top plan view of the same; Fig. 3 is an enlarged view, partly in section, of the landing platform and its operating mechanism, together with the cage and sump guard; and Fig. 4 is an enlarged view of the car-lifting mechanism.

30 In these drawings I have illustrated the preferred form of my invention and have shown the same as comprising a plurality of parallel tracks, preferably two in number, each of said tracks comprising a forward or delivery portion 1, by means of which cars 40 are fed or delivered to the hoisting cage, and a rear or discharge portion 2 which is located at a somewhat higher level than the portion 1 and is adapted to receive the empty cars from the cage and to discharge the same by means 45 of suitable switches to a point where they can be hauled into the mine. Each of these 50 tracks is provided with a car lift comprising a movable track section 3, which, in the present instance, is shown as pivotally connected at one end near the end of the ele-

vated portion 2 of the track and has its forward end extending between the side members of a suitable frame 4, within which it is capable of a free vertical movement. The forward end of the movable track section 3 is 60 preferably bent at an angle to the main portion thereof so that, when the track section is in its lowermost position, the forward portion 5 will lie in a substantially horizontal position and in alignment with 65 the short track section 6 leading from the hoisting shaft. This movable track section is elevated by means of suitable cables 7 secured at one end to said track section and extending upwardly over suitable pulleys 8 70 mounted at the upper end of the frame 4 and secured at their opposite ends to suitable power mechanism, which, in the present instance, consists of a fluid cylinder 9 having a suitable piston 10 and piston rod 11, to the 75 upper end of which the ends of the cables are secured. Each track is also provided with a suitable hoisting cage mounted in the hoisting shaft 12. This cage, in the present instance, comprises a platform 13 carrying the 80 rail sections 14, which, when the cage is in its lowermost position, are adapted to register with the rails 6 of the track. This platform 13 is supported upon a suitable base 15, by means of braces or supporting arms 16. 85

The hoisting cage may be actuated in any suitable manner, it being here shown as provided with hoisting rods or cables 17 which are secured at their lower ends to the base 15 of the cage and extend upwardly to suitable 90 hoisting mechanism. Mounted in the hoisting shaft 12 beneath the hoisting cage is a landing platform adapted to receive the cage, which platform is preferably movable within the shaft and adapted to operate the movable 95 track sections, as well as cushion the descent of the cage. In the present instance, this landing platform comprises a frame 17^a of a size and shape conforming substantially to the interior of the hoisting shaft, and has 100 near its central portion a supporting member or platform 18 adapted to receive the base 15 of the cage. This platform is provided with a downwardly extending standard or support 20 which is adapted to reciprocate within the 105 fluid cylinder 21 and form a piston therefor. This cylinder has extending from a point near its lower end a pipe 22 which serves to connect the same with the upper end of the 110 cylinder 9 of the car-lifting mechanism of the

other track. Thus it will be seen that the downward movement of the landing platform under the influence of the weight of the cage and the empty car thereon will be sufficient to force the fluid from the cylinder 21 through the pipe 22 to the cylinder 9 and thus actuate the piston 10 to elevate the movable track section of the other track. And inasmuch as the track section 3 is greater in weight than the landing platform, the track section will descend as soon as the weight of the cage is removed from the landing platform and thereby cause the landing platform to again assume its normal or uppermost position in readiness to again receive the descending cage. It will further be apparent that, inasmuch as the fluid must escape slowly from the cylinder 21, the descent of the cage with the empty car will be gradually checked, thereby obviating all jar or jolting of the same. Suitable means are also provided for controlling the passage of the cars from the track 1 to the hoisting cage. This mechanism, as here shown, consists of a pivoted rail section 23 having its forward end bent at an angle to the body portion thereof, as shown at 24, and its rear end or main portion pivotally connected to an arm 25, preferably by means of a pin or bolt 26 extending through an elongated slot 27 in the upper end of that arm. The lower end of the arm 25 is pivotally connected to the landing platform, as shown at 28. Thus, it will be seen that when the landing platform is in its normal or elevated position, the main portion of the pivoted track section 23 will be elevated and the portion 24 will be in alinement with the track 1 and will receive a loaded car therefrom, the forward movement of the car being checked by the upwardly inclined portion of said track section. As the cage descends and depresses the landing platform, the track 22 will be moved about its pivotal center and the main portion thereof brought into a substantially horizontal position, preferably to a position slightly inclined toward the cage, thereby allowing the car to move off of the same and onto the cage. In order to prevent the cars on the track 1 from advancing too far while the forward portion 24 of the track section 23 is elevated, a suitable sump guard is provided, which, in the present instance, consists of a curved bar or arm 29 secured at its upper end to the rail section 24 and adapted at all times to occupy such a position that it will form a stop for the cars on the track 1. This arm 29 is preferably provided with a suitable brace 30 extending from the lower end thereof to the track section 24.

60 The operation of the device will be readily understood from the foregoing description and it will be apparent that, when the landing platform is in its uppermost or normal position, the portion 24 of the cage or pivoted track section 23 will be in a position to

receive a loaded car thereon, and, as the cage with the empty car descends it will depress the landing platform and the cage will be moved about its pivotal center and the main portion thereof brought into such a position 70 as to discharge the car therefrom onto the hoisting cage, the rails of which are now in alinement with the rails of the cage. The impact of the loaded car against the empty car on the hoisting cage serves to push the 75 empty car off of the cage and onto the slightly inclined track 6 lying beyond the same which serves to convey the car to the portion 5 of the movable rail section 3 of the lifting mechanism, which rail section is now in its lowermost position inasmuch as the cage of the other or second track is elevated and the movable track section of the first-mentioned track is free to assume its lowermost or normal position. When the loaded car 80 is in position on the cage, the cage is elevated, thus moving the cage 23 into position to receive another car and also permitting the pivoted track section 3 of the second track to elevate the landing platform of that 85 track to its normal position, and, as the cage of the second track descends, it will depress the landing platform of that track and the movable track section 3 of the first-mentioned track with the empty car thereon will 90 be elevated and that car discharged onto the track 2 and thence, by means of suitable switches, to a position from which it can be hauled back into the mine.

I wish it to be understood that I do not desire to be limited to the exact details of construction shown and described, for obvious modifications will occur to a person skilled in the art.

Having thus fully described my invention, 105 what I claim as new and desire to secure by Letters Patent, is:—

1. In a mechanism of the character described, the combination, with a movable track section, and a hoisting cage, of means 110 actuated by the descent of said cage for elevating the adjacent end of said track section.
2. In a mechanism of the character described, the combination, with a movable track section, and a hoisting cage, of means 115 actuated by the downward movement of said cage for inclining said movable track section in a direction away from said hoisting cage.
3. In a mechanism of the character described, the combination, with a movable 120 track section, and a hoisting cage, of a movable landing platform for said cage, and means actuated by the movement of said platform for moving said track section.
4. In a mechanism of the character 125 described, the combination, with a movable track section, and a hoisting cage, of a movable landing platform for said cage of less weight than said movable track section, and means extending between said platform and 130

- said track section and actuated by the weight of said cage on said platform for moving said track section.
5. In a mechanism of the character described, the combination, with a movable track section, and a hoisting cage, of a movable landing platform for said cage, means extending between said platform and said track section and adapted to be operated by the downward movement of said cage for elevating said track section, and means for returning said platform to its normal position when it is relieved of the weight of said cage. 60
- 10 6. In a mechanism of the character described, the combination, with a movable track section, a fluid cylinder having a piston connected to said track section, and a hoisting cage, of a second fluid cylinder connected to the first-mentioned cylinder, and a piston for said second cylinder adapted to be actuated by said cage. 65
- 15 7. In a mechanism of the character described, the combination, with a movable track section, a fluid cylinder having a piston connected to said track section, and a hoisting cage, of a second fluid cylinder connected to the first-mentioned cylinder and provided with a piston, a landing platform connected to the piston of the second cylinder and adapted to receive said cage, whereby said piston is moved within said second cylinder and the piston of the first-mentioned cylinder actuated to elevate said track section. 70
- 20 8. In a mechanism of the character described, the combination, with a movable track section, a fluid cylinder having a piston connected to said track section, and a hoisting cage, of a second fluid cylinder connected to the first-mentioned cylinder and having a piston, a landing platform supported on said piston and adapted to receive said hoisting cage, whereby said piston is moved within said second cylinder and the piston of the first-mentioned cylinder actuated to elevate said track section. 75
- 25 9. In a car handling mechanism, the combination, with a plurality of tracks, a movable track section in each of said tracks, and a hoisting cage for each of said tracks, of means actuated by the cage of one of said tracks for moving the track section of another of said tracks. 80
- 30 10. In a car handling mechanism, the combination, with a plurality of tracks, a movable track section in each of said tracks, and a hoisting cage for each of said tracks, of a movable landing platform adapted to receive the hoisting cage of one of said tracks, and means actuated by the downward movement of said landing platform for elevating the movable track section of the other track. 85
- 35 11. In a car handling mechanism, the combination, with a plurality of tracks, each having a movable track section, a fluid cylinder operatively connected to each of said track sections, a hoisting cage for each of said tracks, of a landing platform for each of said hoisting cages, other fluid cylinders forming supports for said landing platforms, and means for connecting the platform-supporting cylinder of one track with the movable-track-section operating cylinder of the other track. 90
- 40 12. In a mechanism of the character described, the combination, with a movable track section and a hoisting cage, of a fluid-actuated mechanism adapted to be operated by the downward movement of said cage to move said track section. 95
- 45 13. In a mechanism of the character described, the combination, with a movable track section, and a hoisting cage, of a fluid cylinder adapted to be operated by said cage, and means actuated by said fluid cylinder for moving said track section. 100
- 50 14. In a mechanism of the character described, the combination, with a hoisting cage, a cager, and means actuated by the movement of said cage for operating said cager, of a movable track section, and means actuated by the movement of said cage for moving said track section. 105
- 55 15. In a mechanism of the character described, the combination, with a plurality of tracks, a cager in each of said tracks, a movable track section in each of said tracks, and a hoisting cage in each of said tracks between said cager and said movable track section, of means actuated by the descent of said hoisting cage in one of said tracks for operating the cager in the same track, and other means actuated by the descent of said cage for moving the movable track section in another of said tracks.

In testimony whereof, I affix my signature in presence of two witnesses.

GRANT HOLMES.
